(57) **CLAIM**

The ornamental design for a replaceable lighting unit, as shown and described.

DESCRIPTION

FIG. 1 is a front perspective view of a first embodiment of my ornamental design for a replaceable lighting unit.

FIG. 2 is a rear perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left side elevational view thereof.

FIG. 8 is a right side elevational view thereof.

FIG. 9 is a front perspective view of an alternative embodiment of my ornamental design for a replaceable lighting unit.

FIG. 10 is a rear perspective view of the embodiment of FIG. 9.

FIG. 11 is a front elevational view of the embodiment of FIG. 9.

FIG. 12 is a rear elevational view of the embodiment of FIG. 9.

FIG. 13 is a top plan view of the embodiment of FIG. 9.

FIG. 14 is a bottom plan view of the embodiment of FIG. 9.

FIG. 15 is a left side elevational view of the embodiment of FIG. 9; and,

FIG. 16 is a right side elevational view of the embodiment of FIG. 9.

The structures shown in broken lines in FIGS. 1-16 form no part of the claimed design and are included only to illustrate an environment.
